UNITED STATES PATENT OFFICE.

CLARENCE G. FISHER, OF ROCHESTER, NEW YORK.

PAPER-FASTENER.

1,303,279.

Specification of Letters Patent.

Patented May 13, 1919.

Application filed July 11, 1918. Serial No. 244,473.

To all whom it may concern:

Be it known that I, CLARENCE G. FISHER, a citizen of the United States, and residing at Rochester, Monroe county, State of New York, have invented certain new and useful Improvements in Paper-Fasteners, of which the following is a specification.

The present invention relates to paper fasteners of the type comprising a backing member having spaced projecting flexible tongues and a front or top member through which the tongues are passed.

The principal novel features of the invention reside in the provision of a backing member in which the tongues are spaced slightly from the ends thereof whereby the backing member is formed with end portions which bear against the under sheet outside the perforations therein, thus reinforcing the sheet against tearing; in the provision of a backing member having the end portions aforesaid in which the tongues are longer than half the distance between the tongues; in the provision of a backing member having the said end portions and one tongue struck up from the member and being longer than half the distance between the tongues; in the provision of a backing member having the said end portions and a tongue connected thereto by a piece extending from the foot of the tongue to the adjacent end of said member; in the provision of a front member having end portions bearing on the top

sheet of the file throughout the area surrounding the perforations therein; in the provision of a front member having end portions and a connecting part adapted to retain the tongues in bent down position; in the provision of a front member having end portions and a connecting part of less width than the end portions; in the provision of a front member having end portions each formed with an aperture and a connecting part, the joints between said part and portions being offset from the line connecting the apertures; and generally in the provision of a dependable, easily manipulated fastener which requires a minimum of material in its manufacture. Other features of novelty will be apparent from the description taken in connection with the drawings, in which—

Figure 1 is a top plan view of a portion of

a file of sheets held together by a fastener 55 constructed in accordance with the present invention;

Fig. 2 is a sectional elevation taken substantially on the line 2—2 of Fig. 1;

Fig. 3 is a sectional elevation taken substantially on the line 3—3 of Fig. 1;

Fig. 3^a is a perspective view of the front member illustrated in Fig. 1;

Fig. 4 is a perspective view of a modified form of front member;

Fig. 5 is a perspective view of the backing member illustrated in Figs. 2 and 3;

Fig. 6 is a view illustrating in bottom plan a portion at one end of the backing member shown in Fig. 5;

Fig. 7 is a top plan view similar to Fig. 1 illustrating a modified form of front member;

Fig. 8 is a top plan view similar to Fig. 7 illustrating another modified form of front member;

Fig. 9 is a perspective view of a modified form of backing member;

Fig. 10 is a sectional elevation through an end portion of the member shown in Fig. 8⁰ 9; and

Fig. 11 is a perspective view of a file of sheets held together by a fastener including a still further modified form of backing member.

Referring to the drawings and more particularly to Fig. 1, the front member of the fastener there shown comprises the end portions 10 and 11 each formed with an aperture 12 for one of the tongues of the backing member and designed to rest on the top sheet of the file throughout the area surrounding the perforations 13 in the sheet, thus reinforcing the sheet against tearing out from the said perforations. The end portions of the top member are connected by a part 14 of less width than said portions and having a section 15 struck up slightly from the plane determined by end portions 10 and 11. This section 15 is shorter than the distance between the end portions and thus forms notches 16 and 17. In use, the tongues of the backing member are bent down and under section 15 and are thus retained against displacement. Preferably the section 15 projects over about one-half the width of the tongues so that it is an easy matter to manipulate the tongues either to

bend them under the sections or free them therefrom. In this latter operation, the notches 17 afford a space for the fingers to push on the side of the tongues. If desired 5 the part 14 may be reinforced by a rib or corrugation 18 bent out from the said part.

The top member shown in Fig. 4 is similar to that of Fig. 1 except that the tongue retaining section is formed in a somewhat 10 different manner. Thus this top member comprises end sections 110 and 111 each formed with a tongue aperture 112. The part 114 which connects the two end portions has the section 115 struck up from the 15 plane determined by the end portions, and this section is of greater width than the remainder of part 114, thus extending down a sufficient distance so that the tongues may be bent down and under said section in the 20 same manner as described in connection with Fig. 1, and also forming the finger notches 116 and 117.

In Fig. 7 a front member is shown which comprises end portions 210 and 211 formed 25 with the tongue apertures 212 and connected by the part 214, the middle portion of which is wider than the end portions thereby providing an extension 215 and the finger notches 216 and 217. In using this member 30 the tongues are bent down and under the extension 215, the finger notches 216 and 217 forming spaces whereby the tongues are easily manipulated to disengage them from the extension. If desired the part 214 may 35 be reinforced by a rib or corrugation 218.

In Fig. 8 another form of front member is disclosed which comprises the end portions 310 and 311 formed with the tongue apertures 312 and connected by the part 314 40 which is of less width than the said end portions and extends diagonally between them. Thus this part 314 crosses the line connecting the apertures 312 and forms a retaining member for the tongues in a manner similar 45 to that described in connection with the other forms of the front member. Further the arrangement of the connecting part 314 forms notches 316 and 317 for the fingers when disengaging the tongues from the retaining member. If desired the part 314 50 may be reinforced by a lengthwise extending corrugation or rib 318.

In all of the above described forms of the front member, it will be observed that the 55 connecting part is substantially of less width than the width of the end portions and furthermore the joints between said part and end portions are disposed at one side of a line connecting the tongue apertures. Because of this novel construction a very light, 60 but rigid top member is provided and one which permits the tongues to be retained with a minimum sidewise movement of the tongues.

65 Referring to Figs. 2, 3, 5 and 6 the back-

ing member comprises a base 20 having one tongue 21 struck up from the material of the base, thus forming the aperture 22 therein. The said tongue is joined to the base at a slight distance from the end thereof thus 70 providing an end portion 23, which bears against the bottom sheet of the file outside of said tongue thus reinforcing said sheet against tearing out from the tongue perforation. The tongue 24 at the opposite end of 75 the base is stamped out from material which extends beyond the base, as shown in dotted lines at 24' in Fig. 5. This tongue is then bent back on the base 20 and then through the aperture 22 to its right angularly projecting position. Thus the tongue 24 is connected to the base by a part 25 which extends between the foot of the tongue and the adjacent end of the base. In this manner the tongue 24 is disposed so that it projects from 80 the base at a slight distance from the end thereof, thus forming the end portion 26 which rests against the bottom sheet of the file in the same manner as the opposite end portion 23. It will be observed that both 85 tongues 21 and 24 are longer than half the distance between said tongues. Further by striking up tongue 21 from the base a considerable saving in material is made. If desired the base may be reinforced by the longitudinally extending corrugations 27.

Referring now to Figs. 9 and 10 a backing member is shown which comprises the base 28 and the tongues 29 and 30 bent up from material extending from the ends of said 100 base. Thus the tongue 30 is bent from the position indicated at 30' back on the base 28 and thence at right angles to the position shown in full lines at 30. The tongue 30 is thereby connected to the base 28 by a part 105 31 which extends between the foot of the tongue and the adjacent end of the base. The tongue 29 is formed in a similar manner being connected to the base by a part 32 which extends between the foot of the tongue 110 and the adjacent end of the base. In this manner end portions are formed on the base projecting outside the tongues and affording bearing portions which reinforce the bottom sheet against tearing out from the tongue perforations. If desired the doubled over end portions may be secured together by forming an aperture 33 in the base and striking up a tongue 34 from the part 31 through said aperture and bending it down 115 against the under side of the base in the manner clearly shown in Fig. 10. A rib or corrugation 35 may be formed in the base to strengthen the same. The length of the tongues is not limited and as shown are 120 longer than half the distance between them measured along the base.

In the form of the invention shown in Fig. 11, the backing member comprises two similar parts 35^a and 36. The part 35^a has 125

a tongue 37 struck up from the same, the foot of the tongue being disposed slightly from the adjacent end of said part thus forming an end portion 38 bearing against the under side of the file outside of the tongue perforation 39. In a like manner the part 36 has a flexible tongue 40 struck up from the part 36 and disposed to project from said part at a slight distance from the end thereof, thus forming an end portion 41 similar to the opposite end portion 38. The two parts 35^a and 36 are joined together by forming the fingers 42 and 43 at one end of part 35^a, which fingers extend through the slot 44 in part 36 and are bent down against the opposite face thereof. In a like manner one end of part 36 is formed with the fingers 45 and 46 which extend through the slot 47 in part 35^a and are bent down against one face thereof. Thus the two parts are locked together and if necessary at any time the distance between the tongues 37 and 40 may be adjusted merely by sliding one part on the other. It will be observed that the tongues are longer than half the distance between the foot portions thereof and further have the end bearing portions similar to the forms shown in Figs. 5 and 9.

Although several forms have been described in detail, it is to be understood that the invention is not limited to these forms but includes modifications and changes which come within the scope of the appended claims.

Having thus described my invention what is claimed as new and desired to be secured by Letters Patent is:

1. A paper fastener including in combination a backing member having upstanding flexible tongues, a top member comprising end portions each formed with an aperture to receive one of said tongues, the under side of said portions adapted to rest against the top sheet of paper with the aperture in line with an aperture of the paper thus reinforcing the paper against tearing out from its apertures, and a part of less width than the end portions joining said portions, the free ends of the tongues adapted to be bent down and under said part.

2. A paper fastener including in combination, a backing member having upstanding flexible tongues, a top member comprising end portions each formed with an aperture to receive one of said tongues and a part integrally joined to said portions laterally of a line connecting said apertures, the free ends of the tongues adapted to be bent down and under said part.

3. A paper fastener including in combination, a backing member having upstanding flexible tongues, a top member comprising flat substantially rectangular end portions each formed with a substantially centrally arranged aperture to receive one of said

tongues and a part integrally joined to said portions laterally of a line connecting said apertures, the free ends of the tongues adapted to be bent down and under said part.

4. A paper fastener including in combination, a backing member having upstanding flexible tongues, a top member comprising flat substantially rectangular end portions each formed with a substantially centrally arranged aperture to receive one of said tongues and a part of less width than the end portions integrally joined to said portions laterally of a line connecting said apertures, the free ends of the tongues adapted to be bent down and under said part.

5. As an article of manufacture, a top member for a paper fastener comprising flat end portions each having an aperture therethrough, and a part connecting said portions the joint between said part and portions being disposed laterally of a line connecting said apertures.

6. As an article of manufacture, a top member for a paper fastener comprising flat end portions each having an aperture therethrough and a part connecting said portions the joint between said part and portions being disposed laterally of a line connecting said apertures and a section of said part being offset from the plane of the end portions.

7. A paper fastener including in combination, a backing member having upstanding flexible tongues, a top member comprising end portions integrally joined by a connecting part, said portions each formed with an aperture to receive one of said tongues, said part where it joins the end portions being of less width than the end portions whereby the free ends of said tongues may be bent down and under said part.

8. A backing member for a paper fastener including a narrow base and two flexible tongues each projecting from the base at a slight distance from an end thereof, thereby affording a surface on the said member to bear on the paper outside said tongues, one tongue being connected to the base by a part extending between the foot of the tongue and the adjacent end of the base.

9. A backing member for a paper fastener including a narrow base and two flexible tongues each projecting from the base at a slight distance from an end thereof, thereby affording a surface on the said member to bear on the paper outside said tongues one tongue being integrally struck up from the base, and being longer than one-half the length of the base.

10. A backing member for a paper fastener including a narrow base and two flexible tongues each projecting from the base at a slight distance from an end thereof thereby affording a surface on the said member to bear on the paper outside said tongues, one tongue being connected to the base by a part

extending between the foot of the tongue and the adjacent end of the base and the other tongue being struck up from the base.

11. A backing member for a paper fastener including a narrow base and two flexible tongues each projecting from the base at a slight distance from an end thereof, thereby affording a surface on said member to bear on the paper outside said tongues, 10 and each of said tongues being longer than one-half of the length of the base.

12. A backing member for a paper fas-

tener including a narrow base and two flexible tongues each projecting from the base at a slight distance from an end thereof, and 15 each of said tongues being longer than one-half the length of the base, and a part connecting one of said tongues to the base, said part extending outwardly from the foot of the tongue and joined to the adjacent end 20 of the base.

In testimony whereof I affix my signature.

CLARENCE G. FISHER.
